[57] CLAIM

The ornamental design for an ashtray mounted cigarette snuffer, as shown and described.

DESCRIPTION

FIG. 1 is an isometric view of an ashtray mounted cigarette snuffer showing my new design;
FIG. 2 is a top plan view thereof;
FIG. 3 is a front elevational view, the rear elevational view being a mirror image thereof;
FIG. 4 is a right side elevational view, the left side elevational view being a mirror image thereof.
The broken line disclosure of an ashtray in FIG. 1 is for illustrative purposes only and forms no part of the claimed design.
